Primary Examiner — Lucy Lieberman(74) *Attorney, Agent, or Firm* — Lexyoume IP Meister, PLLC(57) **CLAIM**

The ornamental design for a watch, as shown and described.

DESCRIPTION

FIG. 1 is a front perspective view of a watch showing my new design.

FIG. 2 is a front view.

FIG. 3 is a rear view.

FIG. 4 is a left side view.

FIG. 5 is a right side view.

FIG. 6 is a top view; and,

FIG. 7 is a bottom view.

The broken lines in FIG. 3 are used to show portions of the watch that do not form part of the claimed design.
